UNITED STATES PATENT OFFICE.

HENRY SHAW, OF NEW ORLEANS, LOUISIANA, AND JOHN AUSTIN MCCULLOCH, OF GLENCOE, MARYLAND, ASSIGNORS TO THE WELSBAKH INCANDESCENT GAS-LIGHT COMPANY, OF NEW JERSEY.

PACKAGE COMPRISING FRAGILE ARTICLES.

SPECIFICATION forming part of Letters Patent No. 377,644, dated February 7, 1888.

Application filed September 20, 1887. Serial No. 250,252. (Model.)

To all whom it may concern:

Be it known that we, HENRY SHAW and JOHN AUSTIN MCCULLOCH, citizens of the United States, residing, respectively, at New Orleans, in the parish of Orleans and State of Louisiana, and at Glencoe, in the county of Baltimore and State of Maryland, have invented certain new and useful Improvements in Packages Comprising Fragile Articles, of which the following is a full, clear, and exact specification.

This invention has for its object to provide novel means for packing and unpacking articles of a fragile nature such as the skeleton frames or mantles of earthy oxides used as incandescent devices for gas-burners, and fine porcelain, statuettes, and other devices of such fragile material as render them liable to break during transportation—whereby said fragile devices can be safely transported without danger of breaking and be then placed in condition for immediate use. At present there is known the Welsbach incandescent device, consisting of a skeleton hood or mantle composed of earthy oxides, which devices are so extremely fragile in their character as to be easily broken in transportation, and to avoid this is one especial feature of our invention.

The invention consists of a package comprising a fragile article—such as a mantle for incandescent gas-light illumination—entirely incorporated within a solid mass of paraffine or like material, whereby the article is protected from damage during transportation and may be safely unpacked, as hereinafter set forth.

In the accompanying drawings, Figure 1 is a perspective view of a skeleton or perforated incandescent device for gas-burners suspended from its support or holder. Fig. 2 is a perspective view of a foraminous tube used in packing the incandescent devices alluded to. Fig. 3 is a perspective view of an incandescent device with its protecting medium molded thereupon. Figs. 4 and 5 are perspective views, respectively, of a porcelain cup before and after being incased in its molded protecting medium; and Fig. 6 is a vertical sectional view of an apparatus for removing the pro-

teeting medium from the article when the latter is to be used or at any other time.

In order to enable those skilled in the art to make and use our invention, we will now describe the same in detail, referring to the drawings, where—

The letter A indicates a skeleton hood or mantle composed of earthy oxides adapted to be used as an incandescent device for gas-burners by suspending it from the upper end of a wire holder, B, to support the device over a gas-flame. These incandescent devices, as before stated, are extremely fragile, and to transport them in safety and avoid breakage we have devised the following means: A tube, C, preferably tapering, is furnished throughout its area with numerous perforations, and this tube is inserted within the skeleton incandescent device to internally support the same. The incandescent device, with the tube and wire holder B, is then placed in a mold, the internal surfaces of which in no place touch the incandescent device, after which melted paraffine or other wax or similar fusible substance is poured into the mold until it is filled. The paraffine or other fusible material is then permitted to harden and set, and thereby the incandescent device, tube, and wire holder are molded within and entirely covered and concealed by the paraffine, which becomes a protecting medium for the incandescent during transportation. Inasmuch as the incandescent device is entirely within a molded body of the paraffine, which is of such thickness as to prevent jars, shocks, or blows directly acting on the packed device, the latter is thoroughly protected and can be safely transported in a manner more perfect than when these incandescent devices are simply dipped in melted paraffine to strengthen them for transportation.

The molded protecting medium is fused and melted off the packed device when desired to use the latter, and this we accomplish in an efficient manner and save and utilize the paraffine or other wax or fusible material by an unpacking apparatus as follows, reference now being made to Fig. 6, where the letter F indicates a supporting base or pillar, and D a

hollow cylindrical or other shaped case having one open end to rest upon the top of the supporting-base. This base has a vertical passage-way, *f*, and a set-screw, *G*, is tapped laterally through the base, so that its inner end can extend into the said passage-way. An outlet-faucet, *E*, is arranged at the lower end of the cylindrical or other shaped case, and under the outlet-faucet is placed a receiver, *H*, of any desired construction. The device to be unpacked being within the case and the wire rod *B* held in the vertical passage-way by the set-screw *G*, heat is supplied by any suitable means to the upper end of the case, thereby melting the paraffine body *I*, in which the incandescent device is molded. When all the paraffine is melted, the faucet *E* is opened and said paraffine permitted to flow into the receiver *H* for future use in packing other articles. The case *D* is now lifted off the incandescent device, the set-screw *G* is loosened, and the device then removed from the base, after which the internal supporting-tube is removed,

leaving the incandescent in condition for immediate use. In packing other fragile articles, as in Fig. 5, the paraffine can be melted off in our unpacking device or by any other means.

It will be understood that we do not herein claim the apparatus employed in packing and unpacking articles of a fragile nature, as such is reserved for a future application.

What we claim as our invention is—

A package comprising a fragile article—such as a mantle for incandescent gas-light illumination—entirely incorporated within a solid mass of paraffine or like described material, whereby the article is protected from damage during transport and may be safely unpacked, as set forth.

HENRY SHAW.

JOHN AUSTIN McCULLOCH.
